UNITED STATES PATENT OFFICE.

JOHN J. BROWN, OF CHICAGO, ILLINOIS.

PNEUMATIC PUMP.

Application filed January 7, 1926. Serial No. 79,836.

This invention relates to improvements in pneumatically operated pumps.

The primary object of this invention is the provision of an improved type of pneumatic pump which includes the provision of a plurality of liquid dispensing compartments cooperatively arranged in a pressure communicating relation, and embodying cooperative pressure regulating valve and float mechanisms to permit the alternate emptying and refilling of the tanks.

A further object of this invention is the provision of an improved type of pneumatic pump such as is set forth in my Patent #1,551,639, granted Sept. 1, 1925, and embodying specific improvements over the pump apparatus shown in that patent, in the provision of a novel and efficient balancing and operating connection between the exhaust valve mechanisms.

The improved pump apparatus furthermore includes novel operating features which will obviate mechanical float locking means to maintain the same in lower position, and thus including a simplified structure over my patent above referred to.

A further object of this invention is the provision of a pneumatic pump apparatus, embodying a plurality of sets of liquid dispensing compartments, with a common balancing chamber adapted to receive water or a liquid to be dispensed, and embodying pressure communication between the compartments of the tanks via the balancing chamber, with improved valve means for regulating the pressure communication thru said balance chamber.

A further object of this invention is the provision of novel float operated pressure inlet and exhaust valve mechanisms in connection with pneumatic pump apparatus.

Other objects and advantages of this invention will be apparent during the course of the following detailed description.

In the accompanying drawings, forming a part of this specification, and wherein similar reference characters designate corresponding parts throughout the several views,

Figure 1 is a longitudinal sectional view taken thru my improved pump apparatus, showing a pair of pumps, with the left hand liquid dispensing compartment in position for discharging of water or liquid, and the

right hand liquid dispensing compartment full of the water or other liquid.

Figure 2 is a vertical sectional view taken through the pump apparatus, showing the parts arranged differently than that illustrated in Figure 1; the left hand compartment in this view showing the parts in position with the left compartment nearly empty of liquid, and the right hand liquid compartment about to start the liquid discharging operation.

Figure 3 is a view of details of the pump structure as illustrated in Figures 1 and 2, with the parts arranged in different positions than those figures, the left hand compartment or pump structure in this figure being shown with the details arranged for the start of refill of liquid in said compartment, and the right hand liquid dispensing compartment with details in position a short time after the liquid has commenced to discharge.

Figure 4 is a view of details of the pump structure, showing the left hand pump compartment with the same full of liquid, and the right hand compartment discharging liquid.

Figure 5 is a cross sectional view taken substantially on the line 5—5 of Figure 1.

Figure 6 is a cross sectional view taken substantially on the line 6—6 of Figure 1.

Figure 7 is an enlarged fragmentary sectional view showing the valve cooperating parts of the pneumatic pump structure, clearly illustrating the operative relation of pressure inlet and exhaust valves and ports.

In the drawings, wherein for the purpose of illustration is shown only a preferred embodiment of the improved pump structure, the letter A may generally designate the improved pump structure, which comprises tanks or tubes B and C having a head casting or cap D at the top thereof, and a base E, preferably a metal casting. The tubes or tanks B and C are hollow cylindrical in form, and preferably the same dimension, and may be of brass. They are open at both ends, and at their upper and lower ends fit into annular grooves 10 provided in the head D and base E. These tubes or tanks may be threaded into the head and base plates, if desired, but the preferred assemblage is that of providing grooves in which to fit, and connecting the head and base

plates together by means of tie rods 12, which may be positioned either interiorly or exteriorly of the compartments 13 and 14 of the tanks B and C respectively. The 5 tube connections with the head and base plates may have a ground fit, or may be sealed by means of packing.

Preferably integral with the head plate 10 D is a dome or casing 15, providing a balance chamber 16 therein, with ports 17 and 18 which communicate thru the head plate D respectively with the tank compartments 13 and 14. The balance chamber or compartment 16 is thus common to both of the 15 water chambers of the tanks B and C.

The base plate or casting E is provided 20 with bosses 20 and 21, providing pockets 22 and 23 respectively facing the tanks B and C in communicating relation with the compartments 13 and 14 thereof. Ports 25 are provided in these bosses or portions 20 and 21, thru which water inlets from the well to the tanks B and C. Disc valves 26 and 27 are provided for controlling the inlet of 25 water thru the ports 25 into the tanks B and C respectively, and these disc valves are provided with valve stems 28 which are slidably axially of their respective compartments.

30 Liquid discharge conduits or tubes 29 and 30 are disposed in the water compartments or chambers 13 and 14 of the tanks B and C respectively, and extend from close to the bottom of said tanks, just above the valves 35 26 and 27, thru the head D of the pump A. These water discharge pipes extend upwardly thru the water in the well, and it is preferred that the discharge pipe 29 have an elbow 31, and a horizontal connection 32 40 which leads into connected relation by means of a coupling 33 with the pipe 30. The main discharge pipe 35 extends upwardly to any suitable location. Return check valves 36 and 37 are preferably provided in the water 45 discharge lines 29 and 30 respectively.

The tanks B and C are respectively provided with air pressure inlet ports 38 and 39, and the head plate D is preferably provided with bosses 40 and 41 above these 50 ports 38 and 39 respectively, having screw threaded openings therein for detachably receiving the screw threaded lower ends of air pressure conduits or pipes 42 and 43 respectively. The air supply pipes 42 and 43, at their upper ends are provided with elbows 44 and 45 respectively, from which extend nipples 46 and 47, in a connected relation with a special T-type of three way cock 48. The main air supply line 49 enters the other 60 branch of the three-way cock 48, and by a rotary manipulation of the two port cone or valve member 50 of the valve 48, air may be directed selectively to either water chamber of the pump, exclusively of the other, or 65 to both chambers of the tanks B and C si-

multaneously. Normally, the three way valve 48 acts merely as a T fitting, and the air pressure line 49 is opened to both tanks B and C.

From the top of the dome or casing 15 70 extends an air exhaust pipe or conduit 52, which has a screw threaded connection in a screw threaded socket 53 provided in the top of the casing or dome 15. This pipe extends above the surface of the water in 75 which the pump is submerged. A conduit extension 54, preferably integral with the casing 15 depends into the balance chamber 16, preferably axially thereof, having a passageway aligning with the passageway of 80 the exhaust pipe 52, and the lower end of this pipe or extension 54 is open, immediately adjacent the top surface of the head plate D.

Air pressure inlet valves 55 and 56, of 85 the mushroom type, are seated on the head plate D, directly over the ports 38 and 39 respectively, and elongated valve stems 58 are connected therewith, extending thru the ports 38 and 39 respectively, into the tank 90 compartments 13 and 14, for cooperation with certain float controlled means to be subsequently described. It is to be noted that the mushroom air inlet valves 55 and 56 are so associated that their weight will 95 rest upon the said plate D to close the ports 38 and 39, if nothing obstructs the normal tendency of said valves to gravitate to closed position. Preferably integral with the head plate D, and extending below the 100 bottom surface thereof, are lugs 60 and 61, which respectively extend from about the center of the plate D into the compartments 13 and 14 respectively. The lugs are in the nature of a double bracket formed on the 105 head plate, and valve operating levers 62 and 63 are respectively pivoted thereto by means of pins 64 and 65 respectively.

Hollow cylindrical floats 67 and 68 are 110 preferably provided for the compartments 13 and 14 respectively, having connection by means of rods 69 and 70 respectively, with the valve operating levers 62 and 63 respectively, between the ends of the latter; said rods being connected to their respective valve operating lever arms, by means of pins 72. The floats in lieu of being hollow cylindrical, may be of any other approved shape, 115 suitable for the purpose hereinafter described.

120 Exhaust valve tubes 75 and 76 are slidably mounted on the head D, respectively extending freely thru the air exhaust ports 17 and 18, and adapted for air exhausting cooperation and air pressure communicating 125 cooperation with the tanks B and C respectively. Upper and lower brackets 77 and 78 are provided for each of these tubes 75 and 76, having aligning apertures therein for 130 slidably supporting said tubes at their upper

and lower ends in a non-vibratory and definite sliding relation with respect to their respective exhaust ports.

The pilot tubes 75 and 76 preferably extend into the upper portions of the dispensing compartments 13 and 14 respectively, and therein threadably support in a detachable relation exhaust valves 80 and 81, which are of disc formation with the respective exhaust tubes axially arranged thereon. These valves 80 and 81 are preferably provided with ring packing 82, adapted to seat against certain annular projections 83 provided about the exhaust ports 17 and 18 and said valves 15 are adapted when in such position to close the exhaust ports 17 and 18 with respect to their dispensing compartments 13 and 14 of the tanks B and C. The valves 80 and 81 are provided with passageways 85 and 86 there-through, and the said exhaust valves have tubular extensions 87 and 88 at the bottom thereof, thru which the passageways 85 and 86 extend, in aligning relation with the passageways of the tubes 75 and 76. These 20 tubular extensions 87 and 88, in fact form seats against which pilot valves 90 and 91, respectively carried by the float operated levers 62 and 63, may seat, to close off communication of the passageways of the pilot tubes 75 and 76 from their respective tank compartments 13 and 14. The pilot valves 90 and 91 are really formed of rubber discs, held in place by means of adjustable screw threaded plugs 95 and 96, as clearly illustrated in Figure 7 of the drawings.

Referring to the operation of the device, and first referring to Figure 1 of the drawings, air under pressure greater than atmospheric pressure, is fed into the tank compartment 13, from the air pressure line 42, the air pressure inlet valve 55 being held in an elevated relation to open the port 38, by means of the float 67, which is suspended upon the liquid in the compartment 13, in such position as to hold the valve operating lever 62 elevated, as is illustrated in Figure 1 of the drawings. The inflowing compressed air displaces the water from the compartment 13, forcing the same upwardly thru the discharge line 29, and into the main discharge line 35, to any suitable location. The water inlet valve 26 is of course maintained seated incident to the air pressure in the compartment 13, which is greater than the force offered by the head of liquid in which the pump is submerged. The exhaust port 17 is closed by reason of the closed position of its exhaust valve 80, and the passageway of the exhaust tube 75 is also closed by means of its pilot valve 90, the latter two valves being closed over their respective ports and passageway by reason of the holding of the valve controlling lever 62 in an elevated position, due to the buoyancy of the float 67, which has not dropped to such

an extent as to permit opening of the valves, as will be subsequently described. In the other tank compartment 14 the water has filled the same, and it is to be noted that in this position the exhaust port controlling valve 81 has dropped from closed position, so that the tank compartment 14 and the balancing chamber compartment 16 are in communicating relation thru the exhaust port 18, so that the water passes upwardly 75 into the balancing chamber 16, entirely displacing all air from the tank compartment 14, and the water level rises into the balance chamber 16 until the pressure of air entrapped therein is equal to the head of pressure causing the inflow of water, and at which time the water inlet valve 27 will drop, as is obvious. Thus, it is obvious that, as is illustrated in Figure 1, when the tank B has discharged to the extent illustrated, 80 the tank C is filled with water and is inactive. In this position of parts, the force of the buoyancy exerted by the float 68 in its submerged condition is insufficient to unseat the air inlet valve 56, by reason of 85 the air pressure in the line 43 exerting a force sufficient to counteract the force of buoyancy of the float 68. This serves to prevent ascension of the float before the proper time. 95

Continuing with the description of the parts as illustrated in Figure 1, and assuming that the water in the chamber 13 has lowered until the float 67 tends to drop from its position illustrated, and upon any further downward drop of the float 67 the pull exerted thereby will cause the valve lever 62 to move downwardly, to unseat the pilot valve 90, uncovering the passageway 85 and consequently the air pilot tube passageway. It should be remembered, that a hydrostatic pressure exists in balance chamber 16, prior to such unseating of the pilot valve corresponding with depth of submergence of pump, and upon opening of the pilot valve 90, to the position illustrated in Figure 2, air under pressure will rush from the tank compartment 13 upwardly thru the air tube 75, to a point in the air space above the liquid level in the balance chamber. The pressure builds up in this air space above the liquid level in the balance chamber until practically equal to that in the air pressure tank compartment 13. During this operation, which takes place instantly, the increased air pressure in the balance chamber will force some water thru the exhaust line 52. The tube 54, however, is water sealed at its lower end, and the entrance of air into the balance chamber is much more rapid than the escape of an equal volume of water thru the discharge tube 52, during equalizing of pressure between the balance chamber and now practically empty tank compartment 13. Since the pressures are about 100 105 110 115 120 125 130

equal between the balance chamber 16 and compartment 13, the exhaust port controlling valve 80 will now drop, incident to its own weight. It is not forcibly opened, but drops only incident to gravity. The water in the balance chamber 16 can now escape thru the opened exhaust port 17 into water chamber 13.

Practically simultaneous with the above description, is the closing of the air inlet valve 55, which readily closes by gravity to shut off air pressure when the valve controlling lever 62 has dropped incident to falling of the float 67.

Incident to building up of pressure in the balance chamber 16, as above described, thru the pressure communicating tube 75, the pressure in the balance chamber 16 will be communicated to the liquid body in the compartment 14, since it is seen from Figure 1 that the exhaust port 18 is open. The pressure at the inner side of the air pressure inlet valve 56 thus will rise to practically the pressure exerted on the said valve 56 by pressure in the line 43. As above mentioned, the valve 56 is held seated by air pressure thereagainst, and holds the float 68 from rising to its full extent, the force of submergence of said float being exerted against the valve 56 tending to unseat the same. When the pressure is equalized at both sides of the valve 56, as above mentioned, the force of the float 68 opens the air pressure inlet controlling valve 56, so that the air pressure from the line 43 enters the tank compartment 14. Simultaneous with this operation, upon elevation of the float 68, the closing of the communicating port 18 takes place to effectively shut off communication between the balance chamber and the tank compartment 14, as can readily be understood. Upon opening of valve 56 and the air pressure introduction to the tank C, the water will be forced from the tank compartment 14, thru the discharge line 30, into the main discharge line 35.

All of the above operations are practically instantaneous, and the time interval between operations of valves is very small. It is to be noted that all the water in the balance chamber 16 does not exit therefrom until the air pressure regulating valve of the filled chamber has opened, and at this point the air pressure existing in the balance chamber is about equalized with the head pressure in the emptied compartment, so that the communicating port between the balance chamber and tank compartment is open to permit drainage of the water from the balance chamber into the emptied compartment. What water is not forced out through exhaust line 52, drains from the balance chamber into the discharged tank compartment, to break the water seal at the bottom of the tube 54, and the air pressure

which exists in the balance chamber and the now discharged tank compartment 13 exhausts to the atmosphere thru the tube 52.

When the tank compartment 13 is about at atmospheric pressure it is readily apparent that the force exerted by the head of water in which the pump A is submerged will cause the inlet valve 26 to open to permit the introduction of water to the compartment 13 for the filling of the same. As the water level in the compartment 13 rises the float is lifted until the free end of the float connected valve operating lever 62 engages the stem 58 of the air pressure regulating valve 55. The valve 55, however, remains seated, since the air pressure existing in the line 42 is much greater than the pressure in the tank 13, and the buoyant force of the float 67, of itself, is not sufficient to unseat the valve 55, until the air pressures at both sides thereof are substantially equalized. As the water rises to the top of the compartment 13, the pilot valve 90 closes off the passageway of the air pilot tube 75. However, the valve 80 is not closed over the communicating port 17, since the lever arm 62 cannot elevate to such closing position, being held by means of the closed valve 55. This port 17 is open, so that the water may rise, after filling of the compartment 13, into the balancing chamber 16, and the water rises therein until, as above mentioned, the pressure of air entrapped in the top of the balance chamber is equal to the pressure exerted by the head of liquid in which the pump is submerged, and at which time the tank B will be filled, as shown in Figure 4, and the inlet valve 26 will drop by gravity. Water will of course rise in the exhaust line 52, until level with the water of the well in which the pump is submerged. Any further action, towards discharge of water from the tank B, must be initiated by the pilot valve 91 being pulled from its seat over the passageway of the tube 76, whence the cycle of pump operation above described, is again enacted for the tanks B and C. The action of each of the valve arrangements for the tanks B and C, are similar, and it is not believed that any further description of the same is necessary to understand that an automatic operation, and alternate operation of the same takes place, as long as air pressure is applied to the pipes 42 and 43, and so long as the pump is submerged in the well sufficient to enable the water reaching a height in the balance chamber, so that the same will water-seal the main exhaust line at the lower end of the depending conduit 54 long enough to establish equivalency of air pressure between either water chamber, at the time of its ceasing to discharge, and the air pressure of the balance chamber.

The pump is initially started by means of the three-way cock 48, or is again placed

in operation at any time that the same is interrupted. To establish the cycle of operation the cock is turned to act to force said air pressure to either water chamber desired, 5 and it is subsequently turned to supply air pressure to both compartments as soon as one water chamber has been discharged of its water content, and while the other is still full. The valve mechanism operating in a 10 cooperative relation with the float and air pressure maintains the cycle of operation of the pump structure automatic, after once started.

The balance chamber is of such capacity 15 and the submerged sealing tube 54 of sufficiently restricted diameter, as to its passageway, as to insure its being water sealed for a sufficient time to assure the accumulation of air pressure in the balance chamber and 20 the maintaining of the same a proper length of time to enable the valves in both water chambers to maneuver into their respective altered positions as above mentioned. After 25 the unseating of either exhaust valve the greater part of the water remaining in the balance chamber falls by gravity into the respective opened water chamber which has discharged or is discharging.

The invention possesses a novel feature in 30 the provision of the locked float, which is held in position against the force exerted by its submergence, by the pressure holding the air inlet valve upon its seat; the float being only released at the proper instant by the 35 counter balancing of the resisting pressure with an equal pressure in an opposite direction from the tank compartment.

For use in relatively narrow well casings 40 the two water chambers may be arranged in series, or tandem, that is, one above the other. In the tandem arrangement the balancing chamber may be part of the upper water tank, and the lower tank may communicate with the balance chamber thru 45 suitable conduits or pipes, to effect the principle of operation above described.

In lieu of the special three-way cock, suitable angle valves or cocks may be provided in each air line 42 and 43.

50 In lieu of the discharge tube arrangement 52, any other construction may be provided, such as connecting the exhaust line 52 into the bottom of the balance chamber in such manner that no air will escape thru this 55 pipe until practically all the water is out of the balancing chamber.

The pilot tubes 75 and 76 above described are not absolutely indispensable to assure 60 the proper operation of the pump. The air could be made to rise thru the liquid in the balance chamber, by bubbling upwardly thru the water. The tubes 75 and 76, however, serve to quicken the action of operation, and aid in getting the water drained 65 out of the balance chamber quickly after

reversal of cycle of operation is started, and the water seal no longer required. It is to be noted that after the unseating of the air exhaust valves, the air pressure from the respective water chambers continues to pass 70 through the pilot tube, while the water in the balance chamber flows in the opposite direction, draining into the water chamber below, which has been partially or completely emptied. The pilot tube here serves an 75 important function.

The pilot tubes 75 and 76 might, if preferred, rigidly fit in the tops of their respective water dispensing compartments of the tanks B and C. With such rigid arrangement the upper ends of said tubes will be extended to the upper part of the balance chamber, but it is possible that an extra lever would have to be provided for each pilot tube to control the pilot valve 85 thereof.

From the foregoing description of this invention it is obvious that a novel type of pneumatic pump has been provided which operates efficiently, and embodies an automatic operating arrangement.

It is not absolutely essential that the air inlet valves be balanced in the manner above described, if floats of sufficient buoyant power are employed to overcome the resistance of the air pressure holding such valves seated.

In a pneumatic pump embodying the principle of this invention, in which the air inlet valves are not balanced, but in which type of pump the balanced exhaust valve feature is used, the air inlet valves will have stems so short as not to contact with the float lever in ascent of the latter, until the exhaust and pilot valves are practically closed. In this event the air pressure inlet valves may be so designed that the air pressure resistance thereon will only be a fraction of what is necessary when said air pressure inlet valves are used to lock the float and which cannot open until substantially balanced in accordance with the above described feature.

The principles of the invention above described may be applied to the one water chamber type of pneumatic pump, such as set forth in my Patent #1,372,931, dated March 29, 1921, in which case the exhaust valve 80 of the present pump will be balanced by reverse pressure from the balance chamber after the float has dropped and the consequent opening of the pilot tube passageway has resulted, but in such type of pump the air pressure inlet valve will not be balanced, but will only open when the single water chamber has lifted the float member sufficient to exert the required buoyant force to open said air pressure inlet valve.

From the foregoing it will be apparent

that the exhaust valve of either water chamber, or of a simplex pump embodying the principle of this invention, is balanced by reverse pressure from the respective water chamber passing thru the pilot tube into the balance chamber after the float has dropped to unseat the pilot valve. However, as to the air pressure inlet valve of either water chamber, the same is balanced by pressure communicated from the other water chamber by way of the balance chamber which is common to both water chambers, so that in order to accomplish the balancing of air pressure inlet valves at the proper time, a pump of the duplex type is required, in which one water chamber is ready to receive air under pressure for discharging of water when the other water chamber has completed discharge of water and is ready to begin exhausting of air.

Various changes in the shape, size, and arrangement of parts may be made to the form of invention herein shown and described, without departing from the spirit 25 of this invention or the scope of the claims.

I claim:

1. A pneumatic pump comprising a set of submerged receptacles having water inlets and outlets, means establishing pressure communication between the compartments of said receptacles including a balance chamber, air pressure inlet valves for each of said receptacles, valve means for each of the receptacles for controlling both the exhaust of air pressure and inlet of water from the respective receptacles into said balance chamber, a float for each receptacle, and means connecting said floats for operation of said respective valve means above mentioned.

2. A pneumatic pump comprising a set of submerged receptacles having water inlets and outlets, means establishing pressure communication between the compartments of said receptacles including a balance chamber, air pressure inlet valves for each of said receptacles, valve means for each of the receptacles for controlling both the exhaust of air pressure and inlet of water from the respective receptacles into said balance chamber, a float for each receptacle, means connecting said floats for operation of said respective valve means above mentioned, and outlet means for the balance chamber thru which water from the balance chamber may be forced when air pressure is released into the balance chamber from either of the receptacles.

3. In a pneumatic pump the combination of a set of tanks having compartments therein, means at the top of said tanks providing a balance chamber, each of said tanks having a port therein communicating the tank compartments with said balance chamber, air inlet port means for the tank compart-

ments, valves for the air inlet ports of the tank compartments, floats for each of the tank compartments, movable lever means connected with the floats for movement of the valves, valves for each tank compartment for controlling the ports communicating the same with the balance chamber, said valves being positioned for operation by the float connected lever means to close said ports only when the air pressure inlet valves are opened, and valve means to equalize pressure between an empty tank compartment and the balance chamber when the respective float has dropped to a predetermined extent.

4. In a pneumatic pump the combination of a set of tanks, water inlet means in the lower ends of said tanks, water discharge means connected with each of said tanks, means providing a balance chamber above the tanks, each of said tank compartments having a port therein communicating with said balance chamber, an exhaust line communicating in the balance chamber at the lower portion thereof, air pressure means communicating with each of said compartments of the tanks, air pressure inlet valves for regulating air pressure communication with said compartments of each of the tanks, floats for each of the tanks, levers movably connected in each of the compartments of the tanks and connected with said floats, said levers being in the path of the air pressure inlet valves to engage the same incident to rise of the float to a predetermined location to hold the float in a submerged condition incident to inequality of air pressure at opposite sides of the air pressure inlet valves, and valve means controlling the ports which communicate the tank compartments with the balance chamber, said valve means being operatively connected with said lever to permit equalization of pressure between a tank which is substantially empty and the balance chamber, and to maintain the port communication between said balance chamber and either tank compartment open to permit rising of liquid into the balance chamber at a time when inequality of pressure exists at opposite sides of the respective air pressure inlet valve.

5. In a pneumatic pump the combination of a set of tanks having compartments therein, a balance chamber above the tanks having ports communicating with each of the compartments of said tanks, means to supply air pressure to the compartments, air pressure inlet controlling valves for regulating inlet of pressure to the tank compartments, float means for each of the tank compartments, means cooperating with the float means to cause the air pressure inlet valves to open when the float means is buoyantly supported and equality of pressure exists at both sides of the air pressure inlet valves,

- valve means for the first mentioned ports which communicate the tank compartments and the balancing chamber, said means which cooperates with the float means operating 5 said last mentioned valves to shut off the ports which communicate the tanks and balance chamber during discharge of the respective tank compartments, said float means when having dropped to a predetermined extent incident to discharge of water from the tank compartment being adapted to permit opening of the valves which control said ports between the tank compartments and balancing chamber to permit escape of air 10 pressure from a discharging tank into the balancing chamber and thence into the other tank compartment to equalize the pressure at opposite sides of the air pressure inlet valve of said last mentioned tank compartment, 15 said air pressure inlet valves normally being held seated by air pressure during filling of the tank compartments and until air pressure is communicated thereto from the balancing chamber.
- 20 6. In a pneumatic pump the combination of a set of tanks having compartments therein, water inlet means for each of the tanks, water discharge means for each of the tanks, floats in each of the tanks, means for supplying air pressure to each of the tanks, valves for each of the tanks for controlling the air pressure inlet thereto, lever means in each of the tank compartments connected in operative manner to said floats, said lever means being adapted to engage said air pressure inlet valves to normally open the same and hold the same open upon balancing of the pressure at both sides of said air pressure valves, means providing a balancing chamber above the sets of tanks, said balancing chamber having ports communicating with the compartments of each of said tanks, and valve means for said ports operatively controlled by the float connected lever means to close the ports while the air pressure inlet valves of the respective compartments are open, said valves for said ports being adapted to assume an open position when the air pressure inlet valves are closed and holding the float control lever means in position to permit such opening of the port, and means controlled by the float connected lever means to communicate the air pressure in a compartment of a tank which is discharging, when the float of said compartment has dropped to a predetermined extent, to the balancing chamber for increasing pressure in the other tank compartment to equalize pressure at opposite sides of the air inlet valve of the latter compartment.
- 25 8. In a device for elevating water by compressed air, a water chamber having an air inlet opening therein, a valve cooperating with said air pressure inlet opening normally held seated by the air pressure, float means operating in the chamber tending to hold the air pressure inlet valve open responsive to buoyant force of the float means, water inlet means for the water chamber, water discharge means for the water chamber, a second water chamber having an air pressure inlet opening therein, a valve for said opening normally held closed by the air pressure, float means for the second water chamber, said float means of the second water chamber normally tending to unseat its air pressure inlet valve, the air pressure on said air pressure inlet valves being such as to hold the valves closed notwithstanding the buoyant force exerted by the float means until the pressures at each side of said air pressure inlet valves are substantially equalized, a balancing chamber, port means leading from the balancing chamber to each of the water chambers, and valve means operating over said port means and operably controlled by the float means of said water chambers to close off the balancing chamber from the water chambers during discharge of either of the latter, said float means being adapted to open said valve means of the port means when the respective float means has dropped to a predetermined extent, in order to permit air pressure to flow from the discharging water chamber into the balancing chamber for increasing pressure in the other water chamber for equalizing pressures at opposite sides of the air pressure inlet valve therein.
- 30 9. In a device for elevating water by compressed air, a water chamber having an air inlet opening therein, a valve cooperating

with said air pressure inlet opening normally held seated by the air pressure, float means operating in the chamber tending to hold the air pressure inlet valve open responsive to buoyant force of the float means, water inlet means for the water chamber, water discharge means for the water chamber, a second water chamber having an air pressure inlet opening therein, 10 a valve for said opening normally held closed by the air pressure, float means for the second water chamber, said float means of the second water chamber normally tending to unseat the air pressure inlet valve, 15 the air pressure on said air pressure inlet valves being such as to hold the valves closed notwithstanding the buoyant force exerted by the float means until the pressures at each side of said air pressure inlet valves 20 are substantially equalized, a balancing chamber, port means leading from the balancing chamber to each of the water chambers, valve means operating over said port means and operably controlled by the float means of said water compartments to close off the balancing chamber from the water chambers during discharge of either of the latter, said float means being adapted to open said valve means of the port means when the respective float means has dropped to a predetermined extent, in order to permit air pressure to flow from the discharging water chamber into the balancing chamber for increasing pressure in the other water chamber for equalizing pressures at opposite 25 sides of the air pressure inlet valve therein, the valve means for the port means of said balancing chamber being such as to be normally open during the filling of the respective water chambers to enable the water to rise into the balancing chamber, water inlet valve means for each of the water chambers, means to enable discharge of the water from the water chambers when air pressure enters the water chambers, said balance 30 chamber being closed upwardly thereof to enable the water to rise therein when one of the water chambers is filling until the entrapped air in the upper part of the balancing chamber is under pressure substantially equal to the pressure exerted by the water entering the inlet of the water chambers to enable closing of the water inlet valve means of the water chambers and stop water from flowing into the filling 35 water chamber and balance chamber.

10. In a device for elevating water by compressed air, a water chamber having an air inlet opening therein, a valve cooperating with said air pressure inlet opening normally held seated by the air pressure, float means operating in the chamber tending to hold the air pressure inlet valve open responsive to buoyant force of the float means, water inlet means for the water chamber, water discharge means for the water chamber, a second water chamber having an air pressure inlet opening therein, a valve for said opening normally held closed by the air pressure, float means for the second water chamber, said float means of the second water chamber normally tending to unseat the air pressure inlet valve, the air pressure 40 on said air pressure inlet valves being such as to hold the valves closed notwithstanding the buoyant force exerted by the float means until the pressures at each side of said air pressure inlet valves are substantially equalized, a balancing chamber, port

means leading from the balancing chamber to each of the water chambers, valve means operating over said port means and operably controlled by the float means of said water compartments to close off the balancing chamber from the water chambers during discharge of either of the latter, said float means being adapted to open said valve means of the port means when the respective float means has dropped to a predetermined extent, in order to permit air pressure to flow from the discharging water chamber into the balancing chamber for increasing pressure in the other water chamber for equalizing pressures at opposite 50 sides of the air pressure inlet valve therein, the valve means for the port means of said balancing chamber being such as to be normally open during the filling of the respective water chambers to enable the water to rise into the balancing chamber, water inlet valve means for each of the water chambers, means to enable discharge of the water from the water chambers when air pressure enters the water chambers, said balance 55 chamber being closed upwardly thereof to enable the water to rise therein when one of the water chambers is filling until the entrapped air in the upper part of the balancing chamber is under pressure substantially equal to the pressure exerted by the water entering the inlet of the water chambers to enable closing of the water inlet valve means of the water chambers and stop water from flowing into the filling 60 water chamber and balance chamber.

11. In a pneumatic pump the combination of a tank having a liquid dispensing chamber therein, inlet valve means for admitting liquid to the chamber, air pressure means having an inlet port communicating with the water chamber, a valve for the air pressure inlet port normally held seated by air pressure, float means in the liquid chamber of the tank, a movable lever in the tank chamber connected with the float means and adapted to engage the air pressure inlet valve tending to open the same when the float is buoyantly supported in the liquid tank, an exhaust port having communication with the tank chamber, a valve for said exhaust port, said valve being adapted to be held seated over the exhaust port by the lever means, said exhaust port valve having a port therethrough, and valve means carried by the lever means for controlling said last mentioned port.

12. In a pneumatic pump the combination of a tank having a water compartment therein, water inlet valve means for the tank, water discharge means for the tank, air pressure means, said tank having a port for inlet of the air of the air pressure means thereto, an air pressure inlet valve for said port normally held closed by the air pres-

- sure, float means in the tank, lever means operated by the float means, said lever means normally engaging the air pressure inlet valve tending to unseat the same, said 5 float incident to its buoyant force being insufficient to unseat said air pressure inlet valve until substantial equalization of pressure exists at both sides of the air pressure inlet valve, a balance chamber having a port 10 communicating with the tank compartment, an exhaust valve in the tank compartment for said port which communicates between the balance chamber and tank compartment, said exhaust valve being of the gravity operated type to drop incident to its own weight to open the port which communicates the balance chamber and tank compartment, said exhaust valve being normally held closed by means of the float operated 15 lever means, a second port means connected between the balance chamber and tank compartment, a valve for said second port means controlled by the float operated lever means to permit escape of air pressure from 20 the tank compartment to the balance chamber when the tank liquid has dropped to a predetermined level and so that the balance chamber pressure may equalize with the tank compartment pressure to permit drop- 25 ping of the exhaust valve to open the first mentioned port which communicates between the balance chamber and tank compartment. 30
13. In a pneumatic pump the combination 35 of a tank having a water compartment therein, water inlet valve means for the tank, water discharge means for the tank, air pressure means, said tank having a port for inlet of air from the air pressure means 40 thereto, an air pressure inlet valve for said port normally held closed by the air pressure, float means in the tank, lever means operated by the float means, said lever means normally engaging the air pressure inlet 45 valve tending to unseat the same, said float incident to its buoyant force being insufficient to unseat said air pressure inlet valve until substantial equalization of pressure exists at both sides of the air pressure inlet 50 valve, a balance chamber having a port communicating with the tank compartment, an exhaust valve in the tank compartment for said port which communicates between the balance chamber and tank compartment, said 55 exhaust valve being of the gravity operated type to drop incident to its own weight to open the port which communicates the balance chamber and tank compartment, said exhaust valve being normally held closed to 60 close the port by means of the float operated lever means, a second port means connected between the balance chamber and tank compartment, a valve for said second port means controlled by the float operated lever 65 means to permit escape of air pressure from the tank compartment to the balance chamber when the tank liquid has dropped to a predetermined level and so that the balance chamber pressure may equalize with the tank compartment pressure to permit dropping of the exhaust valve to open the first mentioned port which communicates between the balance chamber and tank compartment, said balance chamber having the upper portion thereof sealed whereby upon liquid filling of the compartment and balance chamber the air entrapped in the upper portion of the balance chamber will be placed under pressure until equal to the pressure of the water tending to enter said tank compartment and at which instant the water inlet valve means will close by gravity. 70
14. In a pneumatic pump the combination of a tank having a compartment therein, water inlet valve regulating means in the lower portion of the tank compartment, air pressure means, valve means in the upper portion of the tank compartment to control air pressure inlet to the tank compartment, said air pressure inlet valve means being normally held closed by air pressure, a float in the tank compartment, a lever pivoted in the tank compartment pivotally connected with said float whereby upon lift of the float incident to rising of the liquid in the tank compartment, said lever will engage the air pressure inlet valve normally exerting a force thereon to unseat the same but being incapable of unseating the same until substantial equalization of pressure exists at both sides of the air pressure inlet valve, a balance chamber, said balance chamber and tank compartment having a communicating port, a valve for said communicating port normally gravity operated to drop to open the port, said exhaust valve being in position to be operated by said lever, said exhaust valve having a port therethrough and a tube connected therewith extending upwardly thru the balance chamber, said lever having a valve thereon for regulating opening of the last mentioned port when the float has dropped to a predetermined extent in said tank compartment. 80
15. In a pneumatic pump the combination 85 of a pair of tanks having water compartments therein, water inlet valve means to regulate inlet of water to the compartments, means to permit the discharging of water from said compartments, air pressure means, said tanks having ports therein for inlet of the air pressure from said air pressure inlet means, air pressure inlet valves for said ports normally held seated by the air pressure exteriorly of the tank compartments, floats in 90 each of the compartments, lever means movable in the said compartments connected with said floats and normally bearing against the air pressure inlet valves responsive to the force of the floats incident to 95 100 105 110 115 120 125 130

buoyancy upon liquid in the tanks, a balance chamber having ports communicating with each of the compartments of said tanks, valve means operatively controlled by said 5 lever means for said last mentioned ports to regulate communication between the balance chamber and respective tank compartments, and an exhaust pipe extending into the balance chamber and having an outlet 10 adjacent the lower end of the balance chamber, the upper end of said balance chamber being sealed.

16. In a pneumatic pump the combination of a pair of tanks having water dispensing 15 compartments therein, water inlet valves for each of the tanks in the lower ends thereof, air pressure means having port communication with each of said tanks, air pressure inlet valves for said ports normally held 20 seated to close the ports incident to air pressure, floats for each of the tank compartments, levers pivoted in each of the tank compartments having connection with said floats to move upon rise and fall of the 25 floats, said levers being adapted to engage the air pressure inlet valves of their respective tanks to normally tend to unseat the same responsive to buoyancy of the floats, the buoyancy of the floats never of 30 itself being sufficient to unseat the air pressure inlet valves until equalization of pressure exists at both sides of the valves, a casting providing a balance compartment having ports communicating with each of the 35 compartments of said tanks, valves in the compartments of the tanks for said last mentioned ports, said last mentioned valves being gravity operated to normally drop away from their ports to open the same, said 40 last mentioned valves being controlled by the lever means of their respective tank compartments as to closing of said ports which communicate between the tank compartments and said balance chamber, the air 45 pressure of the tank compartments when greater than the air pressure in the balance chamber being sufficient to hold said last mentioned valves closed, said last mentioned valves having pilot tubes thereon slidably 50 extending into the balance chamber and having passageways therethrough communicating at the upper portion of the balance chamber and at their lower ends having ports communicating in the respective tank 55 compartments, a pilot valve carried by each of the levers of said tank compartments for closing off the ports of said pilot tubes when the floats are elevated in the tank compartments to a predetermined extent, and a dis- 60 charge tube extending into the balance chamber and having an outlet adjacent the lower end of the balance chamber, the upper portion of the balance chamber being normally sealed.

17. In a pneumatic pump the combination

of a tank having a water compartment therein, water inlet valve means for the tank, water discharge means for the tank, air pressure means, said tank having a port for inlet of the air of the air pressure means 70 thereto, an air pressure inlet valve for said port normally held closed by air pressure, float means in the tank, lever means operably connected with the float means adapted to engage the air pressure inlet valve to unseat the same at a predetermined interval of operation, a balance chamber having a port communicating with the tank compartment, an exhaust valve in the tank compartment for said last mentioned port, said exhaust 80 valve being of the gravity operated type to drop incident to its own weight to open the port which communicates the balance chamber and tank compartment, said exhaust valve being normally held closed by means 85 of the float operated lever means, a second port being provided between the balance chamber and tank compartment, a valve for said second port operably controlled by the float operated lever means to permit escape 90 of air pressure from the tank compartment to the balance chamber when the tank liquid has dropped to a predetermined level so that the balance chamber pressure may equalize with the tank compartment pressure to permit dropping of the exhaust valve to open the above mentioned port which communicates between the balance chamber and tank compartment. 95

18. In a pneumatic pump the combination 100 of a set of tanks having compartments therein, means providing a balance chamber, each of said tanks having a port therein communicating the compartment of said balance chamber, exhaust valves for each of the tank 105 compartments for said ports, air inlet port means for each of the tank compartments, air inlet valves for said air inlet port means, floats for each of the tank compartments, movable lever means connected with each of the 110 floats, said exhaust valves being of the gravity operated type to open incident to their own weight to communicate the balance chamber and respective tank compartments, said exhaust valves being normally held closed by the float connected lever means, a second port means connected between the balance chamber and each of said tank compartments, valves for each of said second port 115 means controlled by the float connected lever means to permit escape of air from the tank compartments to the balance chamber when the tank liquid in the respective compartments has dropped to a predetermined level and so that the balance chamber pressure 120 may equalize with said tank compartment pressure to permit dropping of the exhaust valves to open the port which communicates between the balance chamber and tank compartment and permit escape of pressure from 125 130

the said tank compartment into the balance chamber to communicate pressure to the other tank compartment.

19. A pneumatic pump comprising a set of 5 submerged receptacles each having a compartment with a water inlet and a water outlet, valve means for controlling inlet of air pressure to each of said compartments, a balance chamber having ports communicating 10 with the compartments of the receptacles to permit water to enter the balance chamber thru said ports from the receptacles, a valve in each receptacle for the respective port which communicates with the balance 15 chamber to control entrance to and drain of water from the balance chamber with respect to the respective compartment, a float for each receptacle compartment, and valve means operated by each float to control release of air pressure from the respective compartment to the balance chamber.

20. A pneumatic pump comprising a set of 25 submerged receptacles each having a compartment with a water inlet and a water outlet, valve means for controlling inlet of air pressure to each of said compartments, a balance chamber having ports communicating the same with the compartments of the receptacles to permit water to enter the balance 30 chamber thru said ports from the receptacles, a valve in each receptacle for the respective port which communicates with the balance chamber to control entrance to and drain of water from the balance chamber 35 with respect to the respective compartment, a float for each receptacle compartment, valve means operated by each float to control release of air pressure from the respective compartment to the balance chamber, 40 and outlet means for the balance chamber thru which water may be forced from the balance chamber when air pressure is released into the balance chamber from either of the compartments of said receptacles.

- 45 21. A pneumatic pump comprising a plurality of submerged receptacles each having

a compartment with a water inlet and a water outlet, means for feeding air pressure to each compartment including a port for each compartment, a gravity operated air 50 pressure valve for regulating inlet of air pressure to each compartment thru its port, each air pressure inlet valve being normally held seated by the air pressure tending to enter the receptacle compartment until a 55 force is exerted against the valve greater than the weight thereof and to the force of the air pressure tending to enter the compartment, a balance chamber having port communication with each of the compartments of the receptacles whereby to permit water to enter the balance chamber from the compartments thru said ports, a gravity operated valve for each receptacle for controlling the port which communicates between 60 the receptacle compartment and the balance chamber for regulating inlet of water from the compartment to the balance chamber and drain of water from the balance chamber back into the receptacle compartment, said last mentioned valves being of a nature to be held seated when the air pressure in the respective receptacle compartments is greater than the pressure existing in the balance chamber, a float for each receptacle compartment, means controlled by rise and fall of the float to engage the air pressure inlet valve of the respective receptacle for opening the air pressure inlet valve when a sufficient pressure has entered the respective receptacle 70 compartment from the balance chamber sufficient to overcome resistance of the inlet valve, said last mentioned means including a valve arrangement for permitting air pressure to enter the balance chamber from the respective compartment when the float has fallen to a predetermined low level in the respective compartment, and outlet means for balance chamber normally sealed by the water in the balance chamber and thru which water under 75 pressure may vent.

JOHN J. BROWN.
